STEAM IRON CONTROL MEANS

Thomas S. Zastrow, St. Paul, Minn., assignor to
General Mills, Inc., a corporation of Delaware

Application October 11, 1948, Serial No. 53,961

15 Claims. (Cl. 137—587)

1

This application relates to steam irons and more particularly to improved control means for regulation of the supply of liquid in such an iron.

Various methods have been proposed for regulation of the flow of liquid from a suitable supply tank in a steam iron to the customary steam generating chamber. In some cases, it has been suggested that a single control knob be provided which serves both to adjust the setting of the usual valve member and also as a filling opening for replenishing the supply in the tank. In this type of construction there is the problem of preventing leakage or splashing of the contents of the tank in the vicinity of the control member, particularly where the dimensions of the tank and of the valve and control members are subject to small manufacturing variations. If the control member is mounted in one wall of the tank, and the valve member tends to move with respect to that wall during adjustment, it is difficult to maintain the knob in sealing engagement with the wall, unless an expensive and complicated separate knob mounting is provided. Also, where the control knob and iron carry cooperating indicia to indicate the adjustment of the valve member, there is ordinarily no provision for setting the valve parts to correspond to the indicated adjustment. This is particularly troublesome where the valve member is mounted within the tank.

With these problems and difficulties of the prior art in view, it is accordingly one object of the present invention to provide an improved steam iron control mechanism.

It is a further object to provide a construction in which a liquid supply control member is mounted directly on the liquid tank.

A further object is the provision of a construction in which a control member mounted in one wall of a liquid supply tank is operatively connected to a valve member fixedly mounted with respect to a different wall of the tank.

Another object is to provide such a construction with a driving connection between the operating knob and valve member for rotary movement of one by the other which at the same time permits limited longitudinal movement between the parts.

A still further object is to provide an axially resilient connection between such a control knob and valve member to maintain the necessary seal in spite of variations in the dimensions of the parts or the setting of the valve.

An additional object is the provision of a construction in which the relative position of a valve member within the tank may be adjusted without

2

disassembly of the tank, so that the valve setting corresponds with indicia on the control knob.

Another object is a construction of the type described in which the control knob also serves as a filler plug for the tank.

Additional objects and advantages will be apparent from the following specification in which a preferred embodiment of the invention is described by way of example and not limitation.

10 In the drawings which form a part of this specification,

Figure 1 is a side elevation of a steam iron embodying features of the present invention;

Fig. 2 is an enlarged sectional view on the line 15 2—2 of Fig. 1;

Fig. 3 is a perspective view partly in section showing details of the control member according to the invention;

Fig. 4 is a partial perspective view of the top opening in the supply tank; and

Fig. 5 is a sectional view on the line 5—5 of Fig. 2.

In Fig. 1 a steam ironing device has been shown which includes a steaming attachment 10 fastened to the bottom of a regular flatiron 11. The flatiron includes the usual heated bottom plate 12, handle 13, and electrical supply cord 14 connected to the internal electrical resistance which heats the flatiron.

30 The steaming attachment 10 includes a steam soleplate 16 and a liquid supply tank 18. The supply tank is mounted at the rear of the soleplate in a position behind the handle 13 of the flatiron so that it will not obstruct the view of the operator. Side brackets 20, mounted on the rear of the steam soleplate 16, support a horizontal plate member 22 (Fig. 2) connected thereto by screws 24. The supply tank 18 is supported by the brackets 20 and plate member 22.

35 A pipe or conduit 26 carries the liquid from supply tank 18 to the steam soleplate 16 where it is vaporized in a suitable generating chamber 27 so that the resulting steam may pass downwardly through openings 29 in the bottom of the steam soleplate and into the material which is being ironed.

The bottom of tank 18 is provided with a circular opening 28 (Fig. 2) in which the cylindrical stem 31 of a valve member 32 is supported. The 40 portion of valve member 32 inside the tank includes a shoulder 34 which limits downward movement of the stem and valve body with respect to the bottom wall 36 of the tank. A suitable sealing gasket 36 is clamped between the shoulder 34 and the bottom wall 36 to provide

a liquid-tight and air-tight connection at this point.

It will be noted that the lower portion of the stem 31 of valve body 32 extends downwardly through a circular opening in the horizontal plate 22. Below plate 22, the stem 31 is provided with flattened portions defining a non-circular section or wrenching portion 37 (Figs. 2 and 5). A wrenching collar 39, having a corresponding non-circular bore, as at 41, is mounted on the non-circular section. The lower portion 32 of valve body 32, below section 31, is threaded for reception of a suitable lock nut 40. Thus the parts are all clamped firmly together with the valve body 32 fixed in position with respect to the tank and with the tank itself clamped firmly against the horizontal plate 22. Furthermore, the use of the external wrenching collar 39 provides for rotary adjustment of the valve body 32 without disassembly of the parts. This adjustment is an important feature of the invention as discussed in a subsequent portion of this specification.

The lower portion 38 of the valve body includes a hollow bore 42 into which the conduit 26 projects. The conduit is held in position by suitable compression fittings 44 and 46 of known construction. Fitting 44 is likewise threaded onto the lower end of the valve body.

Above the end of conduit 26 the valve body 32 is provided with a central bore 48 which acts as a metering orifice to determine or limit the maximum flow of liquid from the tank to the conduit. At the upper end of this bore 48 a valve seat 50 is provided. Above the valve seat 50 the bore is enlarged as indicated at 51. A plurality of lateral passages 52 communicates with the enlarged bore 51 above the valve seat 50 so that the liquid in the bottom of the tank 18 may reach the valve seat and pass on through the conduit 26 when the valve is open.

The upper portion 54 of the valve member 32 serves as a support for a valve rod 60. Thus the upper portion of bore 51 is further enlarged and is internally threaded as at 56 to receive the threaded portion 58 of valve rod 60. At the lower end of this valve rod there is a valve portion 62 adapted to cooperate with the valve seat 50 to control the flow of liquid to conduit 26.

The upper end 64 of valve rod 60 is operatively connected to a control member or knob 66 mounted in the top wall 68 of the supply tank. Knob 66 is preferably made of moulded plastic material. The main body portion of this control knob 66 is in the form of an annular cylindrical shell 70 which tapers slightly toward the interior of the tank. On the inner surface 72 of this shell-like portion 70 a number of longitudinal projections or splines 74 are provided and these projections are separated by a plurality of longitudinal or axial slots 76. In the present case there are six of the axial projections 74 and six of the corresponding intermediate slots 76, all of which are equally spaced around the internal surface 72 of the shell portion 70 in order that respective pairs of the slots 76 will be oppositely or diametrically aligned.

A pin or key 78 extends laterally through the end 64 of the valve rod 60 and is adapted for selective engagement with any desired pair of diametrically opposite slots 76 in order to provide a driving connection between the knob 66 and valve rod 60 which will result in rotation of the valve rod and corresponding adjustment of the valve seat 62 in response to rotary movement

of knob 66. At the same time the slots 76 will permit limited axial or longitudinal movement of the rod 60 with respect to knob 66 for a purpose described below. The ends of pin 78 engage the inner surface 72 of the knob to prevent accidental removal of the pin.

At the lower ends of the projections 74 in the knob, a series of internal shoulders 80 are provided. The inner or axial surfaces 79 of these projections 74 fit loosely around the body of valve rod 60 and provide a bearing portion in which the rod 60 is axially slidable. The upper or radial surfaces 83 of these projections 74 provide a horizontal shoulder on which one end of a spring 81 is engaged. The other end of spring 81 abuts the lower side of pin 78. Spring 81 is normally under compression so that it tends to cause relative downward movement of shoulders 83 and control knob 66 with respect to the valve rod 60. The purpose of this resilient axial connection between the rod 60 and control member 66 will be apparent from the subsequent description. In the closed position of valve 62, spring 81 is almost fully compressed, so that its coils practically engage each other. Thus the spring provides a positive limit to prevent substantial upward movement of the knob 70, since shoulders 83 engage the spring which in turn engages pin 78. After complete compression of the spring, further movement of the knob 70 away from the valve and tank is prevented.

The upper ends of the longitudinal projections 74 on the interior of control member 66 are provided with threaded portions 82 into which the threaded end 84 of a stopper or filler plug 86 may be screwed. Plug 86 is provided with a sealing gasket 88 to engage the upper portion of the control member 66 and thereby form an air-tight and liquid-tight closure for the upper end of the hollow annular body portion 70 of the member. When plug 86 is removed, the operator of the iron may replenish the supply of liquid in tank 18 by pouring additional liquid through the hollow control member 66. To facilitate the passage of the liquid to the interior of the tank a relatively large lateral opening 90 is provided in the body of the annular shell 70. Opening 90 is located so that its upper edge is at least as high as the top wall 68 of the supply tank 18, in order that the liquid may be completely drained from the tank when the latter is inverted and the plug 86 is removed. Thus the liquid may be removed from the tank when the steam iron is not in use. The use of a plurality of grooves 76 between projections 74 increases the effective cross-section of the filling opening. It also provides extra driving connections between the knob and rod, which may be utilized in case of undue wear of one pair of projections.

To mount the control member 66 in the top of the tank, the top wall 68 is provided with an opening 92 whose internal diameter is slightly greater than the external diameter of the body portions 70 of the control member 66. Preferably the top wall 68 of the tank has an upwardly turned flange 94 around the edge of opening 92.

The upper end of control member 66 is provided with an outwardly and downwardly directed peripheral flange 96 which is spaced slightly from the body shell portion 70 to provide an annular groove 98 into which the flange 94 may project. A sealing gasket 100 is mounted adjacent the outer edge of the flange 94 and serves as a support for the lower inner corner 101 of the flange or shoulder 96.

The width of the groove 98 is so chosen that no part of the body 70 of control member 66 will engage directly with the flange 94 or the top wall 68 of the tank. The control member is supported on the sealing gasket 100 and because the internal diameter of flange 94 is greater than the external diameter of the corresponding portion of shell 70, there is a small annular air space 102 between the respective portions. The supporting flange 96 of the control member 66 is provided with one or more lateral openings 104 which communicate with the internal groove or space 98. Thus a round-about or substantially tortuous air passage is provided between the interior of tank 18 and the outer atmosphere. This air passage includes the narrow annular space 102, the groove 98, and the opening or openings 104. Such an air passage is essential in order to permit downward flow of the liquid within the tank under the influence of gravity, even when the plug 86 completely seals the large central filling opening in the control member.

One or more transverse partitions or abutments 106 may be provided in the space 98 to cooperate with an upstanding lug or stop member 108 on the flange 94 of the tank. Thus the lug 108 may limit the rotation of control member 66 in either direction so that suitable indicia 110 on the upper surface or other portion of the control member 66 will cooperate probably with a suitable index mark 112 on the top of the tank. In the present case, the stops 106 and 108 prevent rotation of member 66 for more than one revolution. It is impossible for the operator to lift the knob far enough to disengage the stops, because the solid or compressed height of spring 84 limits the upward movement of the knob by filling completely the space between shoulders 83 and rod 78 as already described. Thus the original setting of knob 66 cannot be disturbed by the user.

Furthermore, since the resilient connection involving spring 84 tends to urge the control member 66 downwardly at all times with respect to the valve rod 60, the bearing portion 104 of the flange 96 on the control member will always be held firmly against the sealing gasket 100 to provide an air and liquid-tight closure between the control member and the tank wall 68. This tight sealing engagement will be maintained at all times regardless of variations in the initial dimensions due to manufacturing tolerances and regardless of vertical or axial movement of the control rod 60 as it is rotated to adjust the valve portion 62 with respect to valve seat 50.

The adjustment of the valve members so that they correspond to the indicia 110 and 112 on the knob and tank may be readily accomplished without disassembly of the parts. It is only necessary to loosen the lock nut 40. With the valve 62 screwed to its fully closed position, and with pin 76 in driving engagement with the desired pair of slots 78, it is a simple matter to turn the wrenching collar 39 (and with it the valve body 32, valve rod 60, and knob 66) until the indicia 110 and 112 indicate the closed position. Such an adjustment may be made both in initial factory assembly of the device and in later testing of the attachment without disassembly.

A construction has accordingly been provided in which a single control member 66 is operatively connected to a valve actuating member supported within the supply tank 18 so as to maintain the control member in sealing engagement with the tank at all times, while at the same time the

control member 66 provides a means for replenishing the liquid supply within the tank. It is accordingly necessary to provide only a single opening 92 in the upper wall of the tank rather than separate openings for the mounting of a control member and a filling plug respectively. An air passage is provided to permit the gravity flow of liquid from the tank and this air passage is also a part of the control member. Similarly a drainage opening in member 66 permits the complete emptying of the tank for periods of storage. The resilient connection between the valve rod 60 and control member 66 may be established in any one of a plurality of angular positions in case of excessive wear of the plastic parts. And finally, it is a simple matter to adjust the initial setting of the knob and its indicia to correspond to the actual condition of the valve itself, without disassembly of the valve.

Changes and modifications may be made in the specific structure and arrangement of the parts, in the light of the teachings of this application. The present invention is accordingly intended to include all such modifications and improvements as fall within the spirit and scope of the attached claims.

I claim as my invention:

1. A steaming device comprising a liquid supply tank having an opening in one wall and an externally projecting annular flange surrounding the opening, valve means controlling the flow of liquid from the tank and including a valve casing member, a rotatable valve regulating member threaded into the casing member within the tank, a control member rotatable in the opening and having an inwardly projecting peripheral flange cooperating with the tank outside the annular flange to close the opening and to maintain the control member in operative position within the opening, and a direct operative connection between the valve and control members for positive rotation in both directions, the connection including resilient means directly engaging the valve and control members and urging the peripheral flange against the tank, regardless of relative axial movement of the valve member.

2. A steam ironing device comprising a liquid supply tank having an opening and an annular flange surrounding the opening, valve means controlling the flow of liquid from the tank, and including a rotatable valve regulating member within the tank, a control member rotatably mounted in the opening and having a substantially smaller diameter than the opening to provide an annular air passage between the member and flange, the control member having a peripheral flange cooperating with the tank outside the tank flange to close the opening, the peripheral flange being spaced from the body of the control member to provide an annular groove into which the annular flange projects, said annular groove communicating with the annular air space and the peripheral flange having an air vent therein communicating with the groove, means maintaining the control member in operative position within the opening, and an operative connection between the valve and control members for positive rotation in both directions.

3. A steam ironing device according to claim 2, in which the operative connection between the valve and control members includes resilient means urging the peripheral flange of the control member against the tank regardless of relative axial movement of the valve member.

4. A steam ironing device according to claim 2, the control member having an axial filling opening therein and a plurality of angularly spaced axial projections in the opening, and a driving key on the valve regulating member for selective engagement with one of said axial projections.

5. A steam ironing device comprising a liquid supply tank having an opening in one wall and an annular bearing flange surrounding the opening, valve means controlling the flow of liquid from the tank and including a control member rotatable in the opening and having a smaller diameter than the opening and thereby providing an annular air passage between the control member and bearing flange, the control member also having a spaced peripheral flange cooperating with the tank outside the bearing flange and having an air vent communicating with said annular air space, and coacting portions on the peripheral flange and bearing flange limiting relative lateral movement of the control member within the opening.

6. A steam ironing device comprising a liquid supply tank having an opening and a bearing flange surrounding the opening, a rotatable regulating member within the tank, a control member rotatable in the opening and having a smaller diameter than the opening to provide an annular air passage between the control member and bearing flange, the control member having a peripheral flange cooperating with the tank outside the bearing flange to close the opening, a stop member on the bearing flange, an abutment on the control member inside the peripheral flange for engagement with the stop member to limit rotation of the control member, the control member having an air vent communicating with said annular air passage, and an operative connection between the regulating and control members.

7. A steam ironing device according to claim 6 in which the operative connection includes cooperating shoulders on the control and regulating members, and a spring compressed between the shoulders urging the control member and its peripheral flange against the tank, the spring in its fully compressed condition limiting relative outward axial movement of the control member and preventing effective axial disengagement of the abutment from the stop member.

8. A steam ironing device comprising a liquid supply tank having an opening, a valve casing member inside the tank having a projection extending out through the opening, locking means mounting the projection and casing member in fixed position in the tank opening, a valve regulator rotatably mounted in the casing member and having a control member outside the tank, means controlling the rate of liquid flow in accordance with the relative angular adjustment of the regulator and casing member, cooperating indicia on the control member and another part of the device to indicate the condition of the valve regulator relative to the casing, and a wrenching portion on the extending projection for relative rotary adjustment of the casing member to correct the setting of the indicia.

9. A steam ironing device comprising a liquid supply tank having aligned openings in opposite walls, a valve casing member in the tank having a hollow liquid conducting projection extending out through one opening, locking means fastening the projection and casing member in the opening, a valve regulator rotatably mounted in the casing member and having a control mem-

ber rotatable in the opposite opening, means controlling the rate of liquid flow in accordance with the relative angular adjustment of the regulator and casing member, cooperating indicia on the control member and tank to indicate the condition of the valve regulator relative to the casing, and a wrenching portion on the projection outside the tank for rotary adjustment of the casing member to correct the setting of the indicia.

10. A steam ironing device comprising a liquid supply tank having an opening, a valve including a valve member inside the tank with a wrenching portion externally accessible through said opening, a control member outside the tank operatively connected to the valve and having indicia showing the condition of the valve, and means controlling the rate of liquid flow through the valve in accordance with the relative adjustment of the control member and valve member, said valve member being independently adjustable by said wrenching portion to obtain correspondence between the showing of said indicia and the actual condition of the valve.

11. A steam ironing device comprising a liquid supply tank having an opening, a rotatable regulating member within the tank, a control member rotatable in the opening, cooperating stop portions on the tank and control member limiting the relative rotation of the latter and normally capable of disengagement by predetermined relative axial movement of the control member and tank in one direction, and an operative driving connection between the regulating and control members including cooperating shoulders on said members and a spring compressed between the shoulders and normally urging the control member in the opposite direction relative to the tank, thereby maintaining the control member in operative position within the opening, the amount of relative axial movement of the control member required for full compression of the spring between said shoulders being less than the predetermined amount of relative axial movement required for disengagement of said stop portions.

12. A one-piece valve control member and filler for use with a liquid supply tank having an opening and a rotatable valve regulating member inside the tank aligned with the opening, said control member having a cylindrical body portion of diameter smaller than the opening, a radially outwardly projecting flange on said body member for engagement with the tank around said opening, the body portion having an axial filling opening and angularly spaced axially extending integral driving projections in the filling opening for rotary driving engagement with said regulating member, a radially inwardly projecting bearing shoulder at the lower end of at least one of said driving projections, and threaded portions on the upper ends of said projections providing retaining means for a coaxial threaded filler plug.

13. A steam ironing device comprising a liquid supply tank having an opening, a valve including relatively movable valve casing and valve regulating members inside the tank, one of said valve casing and valve regulating members having a wrenching portion externally accessible through said opening, and a control member outside the tank operatively connected to the other of said valve members and having indicia showing the condition of the valve regulating member relative to the valve casing member, the rate of

liquid flow through the valve being controlled according to the relative adjustment of the valve regulating member and valve casing member, and said one valve member being independently adjustable by said wrenching portion to make the actual relative condition of said valve members correspond to the showing of said indicia.

14. A steam ironing device comprising a liquid supply tank having an opening in one wall, valve means controlling the flow of liquid from the tank and including a valve casing member, a rotatable valve regulating member rotatably mounted in the casing member and located within the tank, the casing and regulating members cooperating directly with each other and thereby providing a valve orifice which varies according to the relative rotary adjustment of the regulating member with respect to the casing member, a control member rotatably mounted in the opening and having a peripheral portion co-
operating with the tank wall around the opening to close the latter, and a direct operative connection between the valve and control members for positive rotation in both directions, the connection including resilient means directly engaging the valve regulating and control members and urging said peripheral portion against the tank regardless of relative movement of the valve member.

15. A steam ironing device comprising a liquid supply tank having an opening in one wall, valve means controlling the flow of liquid from the tank and including a rotatable valve regulating member within the tank, a control member rotatably mounted in the opening and having a

5 10 15 20 25 30 35

portion cooperating with the tank around the opening to close the latter, the control member also having an axial filling opening and angularly spaced axial projections in the filling opening, the valve regulating member having a driving key engaging at least one of the projections for rotation of the valve regulating member in both directions by the control member, at least one of the spaced axial projections having a bearing shoulder at one end, and a spring compressed between the bearing shoulder and key urging the control member portion against the tank regardless of relative axial movement of the valve member, said spring also urging the valve member axially in one direction at all times and thereby eliminating lost motion axially of the valve member.
